LOOM ATTACHMENT.

1,142,624.

Specification of Letters Patent.

Patented June 8, 1915.

Application filed January 20, 1914. Serial No. 813,173.

To all whom it may concern:

Be it known that I, PETER REILLY, a citizen of the United States, and a resident of Passaic, in the county of Passaic and State of New Jersey, have invented a new and Improved Loom Attachment, of which the following is a full, clear, and exact description.

The object of the invention is to provide a new and improved loom attachment arranged to insure the formation of a perfect selvage by preventing nicking thereof and to allow forming of fringes by the weft.

In order to accomplish the desired result use is made of a looper controlled by the lay and adapted to engage the weft at or adjacent to the selvage to hold the weft during the return movement of the shuttle, the looper being moved into inactive position by the lay during the beating up movement thereof and the looper returning to active position prior to starting the shuttle through the open shed.

A practical embodiment of the invention is represented in the accompanying drawings forming a part of this specification, in which similar characters of reference indicate corresponding parts in all the views.

Figure 1 is a plan view of part of a loom provided with the attachment, the latter being shown mounted on the temples; Fig. 2 is an enlarged side elevation of the attachment on one of the temples; and Fig. 3 is an enlarged plan view of the fabric and showing the looper in position for holding the weft at one side of the fabric during the return movement of the shuttle.

The loom on which the attachment is used may be of any approved construction, and the loom is shown in Fig. 1 as being mounted on a frame A supporting a cloth beam B on which are attached the housings C' of the usual temples C. The loom is further provided with a lay, the upper part of which is shown in the drawing, D indicating the lay hand rail, D' the reed through which the warp threads pass, and D² the cross bar of the lay proper. The loom is also provided with a shuttle E for carrying a weft thread a through the open shed of the warps b. The attachment is shown mounted on the temples C, and for this purpose each temple C is provided with a transverse stud F on which is mounted to swing the lower end of an arm G having an upward extension G'

arranged in the path of the lay hand rail D so that when the latter moves forward it engages the extension G' and imparts a forward swinging movement to the arm G, as indicated in dotted lines in Fig. 2. The arm G is pressed on by a spring H bearing with one end on the arm G and coiled around the stud F and having its other end attached to the temple C so that when the lay returns a return swinging motion is given to the arm G by the spring H. The return movement of the arm G is limited by the bottom of the extension G' abutting against the top of the temple C.

On the arm G is adjustably secured a longitudinally-extending rod I by the use of nuts I', I² engaging threaded portions of the said rod I, as plainly indicated in Fig. 2. The rear end of the rod I is provided with an eye I² in which is secured the shank of a transversely-extending looper J by the use of nuts J', J² screwing on the threaded portion of the shank and abutting against the opposite faces of the eye I². The inner end of the looper J is provided with a downwardly-extending point or hook J³ adapted to engage the weft a at the back thereof prior to the return of the shuttle E from the corresponding side of the loom. Now when the shuttle returns the weft is looped around the point J³, as plainly indicated in Fig. 3, and consequently the loops a' of the weft a are not liable to be drawn inward on the adjacent warps b thus preventing nicking of the fabric at the edge or selvage thereof. By making the looper J adjustable in a transverse direction the point J³ may be moved nearer to or farther from the outermost warp b thus causing a fringe to be formed by the weft a at the edge of the fabric.

It will also be noticed that by adjusting the looper J in a transverse direction the point J³ may be set to pass between the outermost warps b if it is desired to do so, it being understood that even in this case the loops a' formed by the weft a are prevented from nicking the selvage or side edge of the fabric. When the lay moves forward for beating in the weft the lay hand rail D engages the extension G' of the arm G thus imparting a forward swinging movement to the arm G whereby the rod I is swung upward and with it the looper J so that the point J³ thereof moves out of engagement

with the loops a' of the weft a . When the lay returns, the arm G, and with it the looper J, swings downward by the action of the spring H so that the point J^3 engages the beaten-in weft a at the back thereof immediately prior to the shuttle passing through the open shed on its return movement relative to that particular side of the loom.

10 It is understood that two loopers J are used, one on each side of the fabric to produce the desired result, that is, to prevent nicking of the selvage and to form fringes by the weft at the edges of the fabric.

15 The attachment is very simple in construction and can be readily applied to looms as now constructed.

Having thus described my invention, I claim as new and desire to secure by Letters Patent:

1. In a loom, the combination with a lay having a lay hand rail, a temple, an arm mounted to swing on the temple and extending into the path of the lay hand rail, and 25 a looper held on the said arm and adapted to engage the weft to hold the latter during the return movement of the shuttle, the said arm being swung by the lay hand rail to move the looper out of engagement with the 30 weft loop during the beating up movement of the lay, the said arm having means for engaging the temple to limit the return movement of the arm.

2. In a loom, the combination of a lay 35 having a lay hand rail, a temple, a spring-pressed arm mounted at its lower end to swing on the temple in the direction of the length of the loom, the said arm having an upward offset extension arranged in the path 40 of the said lay hand rail, and a looper held on the said arm and having a downwardly-extending point adapted to engage the weft during the return movement of the shuttle, the bottom of the arm extension abutting 45 against the top of the temple to limit the return movement of the arm.

3. In a loom, the combination of a lay having a lay hand rail, a temple, a spring-pressed arm mounted to swing at its lower 50 end on the temple in the direction of the length of the loom, the upper end of the said arm being in the path of the said lay hand rail, a longitudinally extending rod adjustably held at its forward end on the said 55 arm and extending rearwardly, and a looper having a shank and a point, the said shank

extending transversely and being adjustably secured in the rear end of the said rod and the said point extending downwardly to engage the weft.

4. In a loom, the combination of a lay having a lay hand rail, a temple, provided with a transverse stud, an arm mounted to swing at its lower end on the said stud, the arm having an upward extension arranged 65 in the path of the lay hand rail, whereby a forward swinging movement is imparted to the arm when the lay moves forward, a spring coiled around the said stud and bearing with one end on the said arm and having 70 its other end attached to the temple, the said spring giving a return swinging motion to the arm when the lay returns, a longitudinally extending rod adjustably secured at its forward end on the said arm, the rear end of 75 said rod being provided with an eye, and a transversely extending looper having a shank adjustably secured in the said eye, the looper having at its inner end a downwardly extending point adapted to engage the weft 80 on the return movement of the said arm, the arm extension being offset from the body of the arm and forming a shoulder engaging the top of the temple to limit the return movement of the arm.

5. In a loom, the combination with a lay having a lay hand rail, and the loom temples having studs projecting therefrom, of arms pivoted on the said studs to swing in the direction of the length of the loom, the said 90 arms extending in the path of the lay hand rail, and loopers carried by the said arms.

6. In a loom, the combination with a lay having a lay hand rail, and the loom temples having transverse studs projecting therefrom, of spring pressed arms pivoted at 95 their lower ends on the said studs to swing in the direction of the length of the loom, the upper ends of said arms being in the path of the said lay hand rail, rods adjustably held in the said arms above the pivots thereof and extending rearwardly from the arms, and loopers adjustable transversely in the rear ends of said rods.

In testimony whereof I have signed my 105 name to this specification in the presence of two subscribing witnesses.

PETER REILLY.
